UNITED STATES PATENT OFFICE.

JOHN T. MCGRATH, OF BLOOMINGTON, ILLINOIS.

FLUE CLEANING, CUTTING, AND HANDLING MACHINE.

Application filed August 25, 1924. Serial No. 733,877.

This invention relates to improvements in machines for cleaning boiler flues and other like uses, and of that type in which the external scale is removed from the flues by the application of a series of cleaning elements adapted for engagement with the exterior of the flue through relative rotation of the flue or elements when in contact.

10 An object of the invention is to improve his general type of flue cleaner with respect to simplicity of construction and operation; speed of cleaning the flues; speed of applying the flues to the machine and removing them therefrom; to a novel cleaning element unit, embracing independently rotatable, toothed rolls rotative on coaxial axes; to means for connecting the flues to a rotative driving part whereby they can 20 be rotated against the cleaning elements; to means for varying the cleaning pressure on the flues; to means for advancing plural cleaners toward and retracting them from the flues; to pneumatic means, controlled by 25 valves and located at a fixed operator's station to actuate the several elements of the machine; to means for supporting the flues in the machine, adapted to operate on flues of different lengths; to means for adjusting 30 the flues on and removing them from said driving mechanism; to means for cutting the flues while in the machine in readiness for welding and for enabling the cut ends to be removed so that safe ends can 35 be welded to the flues while in the machine; and to otherwise simplify and improve flue cleaning machines.

In the drawings hereto appended is illustrated an embodiment of my invention wherein the elements of the invention are assembled to produce an operative machine embodying the principles of my invention, but it will be understood that the details of the present embodiment, and which are hereinafter specifically described, may be varied within the scope of the claims hereto appended without departure from the spirit of the invention, and that it is the intent to claim all of inherent novelty shown in the drawings and described in the specification.

In the drawings:

Fig. 1 is a plan view of a machine embodying my invention, broken away to preserve a readable scale within the required dimensions.

Fig. 2 is a side elevation thereof broken away.

Figs. 3 and 4 are transverse sections on the respective lines 3—3, 4—4, of Fig. 1. 60

Fig. 5 is a longitudinal section partly broken away on line 5—5 of Fig. 1.

Fig. 6 is a transverse section on line 6—6 of Fig. 1.

Figs. 7 and 8 are detail sections on lines 65 7—7 and 8—8, respectively, of Fig. 1.

Fig. 9 is an end view of the machine looking toward the front end thereof.

Fig. 10 is a broken transverse section on line 10—10 of Fig. 1. 70

Figs. 11 and 12 are, respectively, transverse and plan views of the machine showing the application of a tool and its appliances to perform in the machine, the end and cylindric facing of the flue in readiness for 75 welding in a flue welding machine.

Figs. 13 and 14 are details taken on the respective lines 13—13 and 14—14 of Fig. 11.

Fig. 15 is a detail longitudinal section of the machine showing the flue lifting saddles 80 and their operating means.

Fig. 16 is a fragmentary section on line 16—16 of Fig. 1.

Fig. 17 is a vertical detail section on line 85 17—17 of Fig. 16.

Fig. 18 is an enlarged longitudinal section on line 18—18 of Fig. 3.

Fig. 19 is an enlarged transverse section on line 19—19 of Fig. 5.

Fig. 20 is a fragmentary side elevation of the flue driving chuck, partially broken away.

Fig. 21 is a fragmentary detail of one of the jaws of the flue driving chuck.

The frame of the machine comprises front and rear pedestals 10, 11 and intermediate pedestals 12, on which are supported and to which are fastened parallel frame bars 13 of channel cross section with their flanges directed outwardly to constitute between them a longitudinal upwardly opening chamber 14 within which are disposed flue cleaning elements and into which the flues are placed for cleaning between said elements and from there removed. The frame bars 13 can be connected at their lower sides, and at places at their upper sides, by cross connecting pieces which, taken with the attachment of said bars to the pedestals, produce a strong frame structure. 15 designates a hopper beneath the cleaner chamber having a hinged door 16, suitably hinged to the proper sup-

port, the door being made in sections and each locked by a lock 17. In the description of the machine which follows, that end of the machine at the left (Figures 1 and 2) 5 will be termed as the front of the machine; the other being termed as the rear of the machine. The supporting pedestals may take on any suitable form but the intermediate pedestals are shown as fabricated to support the air cylinders 18, whose function it is to raise and lower the flue supporting saddles 19, as will be hereinafter more fully described.

Primarily, it may be said that the valve 15 controls, which are located at the front of the machine, embrace a plurality of valve casings or boxes 20, 21, 22, 23, 24, 25, herein being shown six in all. Each one is operative to control a given function of the machine, as will hereinafter appear, and said valves are operated by handles 26, 27, 28, 29, 30, 31. These valve handles are of general L-shape in side elevation, as will appear from an inspection of Figures 7 and 8. Some of 20 them have elongated toes 32 (Figure 7) disposed at a right angle to the handle to engage and depress an associated valve stem, and are pivoted to the boxes in such a way that they are quickly opened by suitable 25 springs after valves have been opened thereby through manual power. Others of said handles have cam shaped toes 33 (Figure 8) to bear on their associated valve stems, and their pivots are so disposed that when the 30 levers are swung inwardly past centers of their pivots, as shown in dotted lines in Figure 8, the cam shaped toes become operative to lock open the associated valves, as will hereinafter appear.

40 Each valve is a duplicate of the other, except that some are operated by the cammed levers and are adapted to lock their valves opened after manual pressure is released, while others have a quick snapping closing.

45 The connection of each valve to the mechanism which it controls will hereinafter be explained in association with a particular function of the machine to be controlled by said valve. In the following description of the 50 internal mechanism of one valve will serve as a description for all of the valves, the valve structures being best shown in Figures 1, 2, 6, 7, 8 and 9, wherein it will be seen that the series of said bodies are mounted on a 55 horizontal bracket 34 extending laterally from and fixed to a side bar 13.

The details of a valve structure are shown in Figs. 7 and 8, and will now be described.

Each valve body, with a downwardly 60 opening inlet chamber 35, is attached to a bracket 34 by the screws shown, and there is an air tight fit between the valve body and the bracket, as by a packing between the parts. Air is continuously delivered at 65 working pressure to the valve chambers 35

through laterals 36 in open communication with a manifold 37 connected to a suitable source of air under pressure. Each valve body is provided above the inlet opening with an outlet opening 38, to which is connected an outlet air supply pipe 39 which leads to mechanism whose operation is controlled by said valve; all said latter pipes, for convenience, being, for simplicity, designated by the same numeral. Between the 70 inlet and outlet chambers of the valve body is formed a shoulder 40 that constitutes a seat for a main cut-off valve 41. Said valve is normally urged against said seat by a spring 42. The stem 43 of said valve 41 extends upwardly into the outlet chamber 38 and into a downwardly opening cup 44 and is slidably in said body, there being a light spring 45 interposed between the end of the main valve stem and the bottom of the cup. Extending upwardly from the cup and preferably made integral therewith is a contact stem 46 which is actuated by contact with the toe 32 or 33 of the lever 28 or 27. As before stated, the toes of these levers are 80 of different formation, the toes 32 being disposed at right angles to the axes of their handles, and the pivots 47 of these latter levers are disposed at the angle of the toes and main shank portions of the valve levers. 85 Therefore when manual pressure to open these valves is released the springs 42 snap the valves 41 closed firmly. The toes 33 of the lock down valve handles are cam shaped and are integral with their hand pieces. 90 They are pivoted at 48 to fixed parts of the valve assembly, so that when the levers having the cam shaped toes are swung inwardly on their pivots to swing their contact portions past their pivots, the cams will automatically lock open valves associated therewith. The contacting stems 46 of the valves extend upwardly into notches 51 of the castings constituting the valve bodies and the 95 toes of said levers vibrate on their pivots 100 in said notches. The contact stems 46 extend sufficiently above the floor of the notches to give ample movement to said stems and their operating levers to properly open the main valves against their seating 105 springs 42.

Each valve is formed with an exhaust port 55, and said port is located below the normal position of the skirt of the cup 44 into which the upper end of a valve stem 43 extends for bearing contact with the spring 45. In operation of the valve, downward movement of the contact stem 46 first acts against the lighter spring 45, to depress said cup 44 downwardly past the exhaust port 55, so that in the continued movement of the two part valve stem thus contrived, the port 55 will be closed by said cup 44 before the main valve 41 is shifted off its seat against the action of the stronger spring 35 to es- 110 115 120 125 130

tablish communication between the inlet and outlet chambers of the valve, and also to establish communication to the outlet pipe and against a piston of the mechanism controlled thereby. Should other means be employed for controlling the exhaust 55, the valve stem could be made solid. It will be noted that the laterals 36 enter the inlet chamber of the valve bodies eccentrically so as to avoid obstruction of air flow when the guide studs for the spring 42 are in their lowermost positions.

Within the upwardly opening tube chamber 14 are mounted a group or series of cleaner rolls 60, shown in detail in Figure 18 and as assembled on the machine in Figure 1. These rolls are circumferentially grooved and are sharpened to produce spiral cutting edges 61, and are also longitudinally recessed at 62 to produce abrupt cutting projections at the intersections of the circumferential grooves and longitudinal recesses. Each group of cleaner rolls embraces a plurality of cylindric toothed members which are separately rotatable on their axes so that different points along the teeth progressively strike the scaled flue to be cleaned, and so also that the longitudinal recesses 62, producing the abrupt cutting teeth, will be varidly spaced angularly about the rolls and thus produce the periods of cutting impact of the rolls against a positively driven flue and more effectively deface the scale therefrom.

The rolls of each group are suspended through the shafts 63 and parallel arms 64 (Figure 3) of a suspending bracket, the arms of which are pivoted on a rod 65 supported in a U-shaped bracket 66 fixed in any suitable way to the inner side of the frame bars 13. The arrangement is such that the cutter rolls tend to swing away from the flue and tend to drop away therefrom by gravity, but are positively but resiliently forced into engagement with the flue. There are a series of such cutting roller groups along both sides of the chamber 14, and groups at one side of the chamber, as a whole, are preferably disposed in staggered relation relatively to the groups at the other side of the chamber, so that the flue is properly covered along its entire length to be cleaned.

Said groups of cleaner rolls are disposed above a plurality of cradle rolls 75, which are properly spaced along the bottom of the chamber, there being a sufficient number of these rolls and preferably spaced apart to support flues of different lengths, when a flue F is connected to its driving mechanism which turns the flue against the cleaner rolls. The flue is thus rotated by connection at its front end with a positive driving clutch 77, hereinafter to be described, while the flue is resting on the cradle rolls or upon the cutters themselves when the thickness of the

scale is such as not to permit the flues to pass between the cleaner rolls when most widely adjusted from each other. Remembering that a flue is positively driven by the clutch 77, hereinafter to be described, and that the flue is resting at its free end on the series of cradle rolls, the said cutter rolls are resiliently held against the uncleared flue by mechanism made as follows:

78, 78 designate thrust bars which are arranged longitudinally along and outside the sides of the channel member 13, and are parallel thereto. They are supported in guide 79 fixed to and extending laterally from the frame bars 13. 81 (Figure 18) designates a laterally disposed thrust pin associated with each set of rolls. Each pin extends laterally and loosely through the bracket 79 and the associated channel plate 13. It is provided with a beveled outer end to engage an inwardly beveled or cam face 82 of the thrust bar 78, and extends inwardly through the bracket 79 and through the frame bar 13 for connection to a spring 83 (Figure 18), herein shown as having the form of a semi-elliptical spring. Each spring engages at its ends the sustaining roll carrier in the manner shown in Figure 18, and the bracket is provided with an opening 84 through which the inner end of the thrust pin can pass when power is exerted thereon to force the cutter or cleaner rolls inwardly towards the flues. In this position the spring 83 will be flattened. There are a number of cam surfaces 82 at each side of the machine opposite and to correspond with the number of cutter roll groups. It will, therefore, be evident that when the thrust bars 78 are forced forwardly from the position indicated in Figure 18, the pins 81 will be thrust inwardly to act against the cushioning springs 83 to force the cutter rolls against a flue seated on the cradle rolls. Conversely, when the thrust bars 78 are moved rearwardly, the cutter rolls will be released from the flues, the release being permitted by the straightening of the springs 83 and gravity of the rolls at their mountings.

The means for actuating said thrust bars 78 to move them forwardly and rearwardly are made as follows:

87 designates a rock shaft mounted in bearings below the channel bars 13, near the front end of the machine. 88 designates a crank arm fixed to one end of said rock shaft. 89, 89 designates arms fast to and extending upwardly from the rock shaft, one at each end of said shaft. Said arms are connected at their upper ends to the forward ends of the thrust bars by loose or hinged connecting joints 90. A link 91 is connected at its ends to said crank arm 88 and the rod 92 of a piston 93 which reciprocates in a cylinder 94 that is bracket connected to the front pedestal of the machine.

In said cylinder 94 at the sides of said piston are air connecting nipples 96, 97, the former being connected through the pipe 39 to its associated valve 22, and the other 5 connected through pipe 39 to its associated valve 21. When air has been admitted through the nipple 97 through the action of the valve lever 27 to the front end of the cylinder 94, the force of the air acts through 10 the thrust bars and pins to force the cutter rolls towards the flue, which can be rotated between the rolls, through the action of the drive clutch 77 referred to. The hand lever for this movement of the cleaner rolls 15 towards the flue, is a cammed lever and locks the valve open for continuous action of the rolls on the flue. Upon partial closing of the connection through nipple 97 to air, which is accomplished by partially 20 swinging back of the lever 27, and to, at the same time, open the valve 21 to admit air through inlet 96 to the other side of the piston 93, the thrust bars will be shifted in a direction to cause the inclined ends of the 25 thrust pins 81 to travel down on the cam surfaces 82 of the thrust bars and thereby permit the cutter rolls to be released from the rotating flue. An adjusting nut (Figures 1, 2 and 3) 98 is threaded to that portion 30 of the front end of the piston rod 92 which extends through the cylinder and the adjacent stuffing box. Surrounding said rod 92 between said adjacent stuffing box and the nut 98, is a sleeve 92' and projecting 35 from the adjacent end of the cylinder which serves in connection with said nut to limit movement of the thrust bars in a direction to force the cutter rolls toward each other; and this movement can be varied to 40 adjust the cutters to flues of different diameters or having different thickness of scale coating. The employment of sleeves 92' of different lengths will vary the range of adjustment of the cutters. 45 The flues are disposed into flue cleaning position by first placing them on saddles 19, two herein shown, that surmount the upper ends of rods 101 when the saddles are raised upwardly to the top of the chamber 14, and 50 then dropping them down to cleaning position. As shown, the lower ends of the rods 101 extend through stuffing boxes into vertical cylinders and have at their lower ends pistons 103 (Figure 15). The cylinders are 55 mounted on the intermediate pedestals, as shown in Figure 15. Air is admitted to said cylinders below the pistons 103 to raise the saddles to receiving position. Wherefore air can be allowed to slowly escape from the 60 cylinders to permit the pistons and saddles to drop, with the flue thereon, in cleaning position relatively to the cleaner rolls. 112 designates a cross pipe which extends between and is connected at its ends to the 65 lower ends of said cylinders, and said cross

pipe is connected by one of the connecting pipes 39 with the valve 23. This valve has a cam-shaped toe that bears on the engaging stem of its valve structure to hold the valve open and to thus hold the saddles 19 raised 70 in position to receive the flues, the valve being locked during the time the saddles are loaded. Thereafter said valve 23 can be closed slowly, and, assisted by gravity, the parts carrying the flue will be allowed to 75 drop in position to bring the flue in cleaning position. The flue finally drops until its weight is borne by the series of saddle rollers 75. Therefore, the saddles 19 are raised by admitted air beneath the pistons, 80 and the saddles will be locked in their upward positions until the clean flue is removed and until a scaled flue is loaded on the saddles preparatory to lowering the flue into cleaning position. 85

When the flue in its cleaning position is disposed with its reduced end opposite to the holding and driving chuck 77, it is thereafter forced endwise on the chuck and the chuck is expanded to produce a driving connection between the flue and chuck. The flue shown is reduced at one end. The mechanism for so connecting the flue to driving mechanism to rotate the flue in cleaning position is made as follows: 90

120 (Figure 5) designates a cylindric tubular body constituting part of the front end of the machine. It is coaxial with the rotative axial position of the flue. Fast to or made integral with the front end of said body is a pulley 121, through which power may be applied to rotate the flue driving chuck hereinafter described. The pulley body is formed with a cylinder 122, closed at its inner end by an integral wall having a stuffing box for the passage of the stem 123 of a piston 124 that reciprocates in said cylinder 122. The said cylinder is closed at its outer side by a plate 125, which carries an air passage 122' which communicates with said cylinder in rear of the piston 124 and is connected by one of the pipes 39 with the first valve 20 of the bank of valves, and is operated by a cam lever of the kind shown in Figure 8. Opening of the 115 valve reciprocates the piston 124 outwardly. Said tubular body 120 is reduced at its rear end at 128 over which fits a supporting and guide sleeve 129 constituting part of the flue driving chuck 77 before mentioned. 120 The stem 123 in the body 120 extends backwardly into the bore of the reduced end 128 and is provided at its inner end with an outwardly tapered endwise adjustable cone 130 which is movable with the piston 124 and coaxial therewith. The exterior face of said cone is adapted to the inner oblique faces of chuck pins 131 which extend through registering openings in the sleeve 129, and the reduced end of the body 120, said pins 130

- having heads 132 which lie normally in sockets in the periphery of the sleeve 129 (Figures 19 and 20). Said sleeve 129 is tapered at its rear end for the flue to pass thereover.
- 5 A cone helical spring 135 lies between the piston end and the plate 125, constituting the front end of said cylinder 122. Said spring is compressed when the piston is moved outwardly, and the stored power of 10 compression serves, when the valve 20 is closed, to force the piston 124 inwardly and thereby unclutch said clutch 77 from the small diameter of the tube end.
- In disposing the flue F in driving relation 15 to the chuck, the flue is first centered relatively to the chuck after it has been allowed to descend to cleaning position.
- It is then pushed endwise on the chuck by means hereinafter described. Thereafter, 20 air is admitted through the valve 20 in rear of the piston 124 so as to cause said piston and said cone 130 to travel outwardly, the latter along the inclined ends of the clutch pins and thus throw the heads thereof 25 (which are transversely exteriorly roughened) out against the inner wall of the reduced portion of the flue. In this way the flue is chucked to the flue driver. Air is admitted in rear of the piston 124 through 30 the inlet port 122' which is connected to one of the valve pipes 39 that is in turn connected to the chamber 35 of the valve 20.
- Going back, now, to the means for forcing the reduced end of the flue on the chuck 35 77, the same is made as follows:
- 140 designates a thrust plate that is adapted to engage on the rear open end of the flue when in its cleaning position. 141 designates a rearwardly extending stem which 40 extends through a stuffing box in an adjacent wall of a push on cylinder 142 that is disposed and supported in any suitable manner, as by the bracket 142', centrally of the frame, and to which is fixed a piston 45 143 that slides in said cylinder with a packing fit. 144 designates a guide pin which is fixed at its rear end to said thrust plate and at its front end to the piston 143 eccentrically with respect to the piston rod 141.
- 50 This pin 144 serves to hold the thrust plate fixedly on the piston rod 141 and relatively to said piston. A spiral compression spring 145 surrounds said piston rod within the cylinder at the front end of the latter and 55 serves two functions—one to cushion the forward stroke of the plate 140 against the end of the flue when air is admitted through the inlet pipe 39 and 146 to thrust the flue on the chuck, and the other to release said 60 thrust plate from the flue when air is disconnected from the cylinder on the rear side of said piston. A long flexible hose 150 connects air between the pipe 39 and the rear end of the connection 146 and enables the 65 said cylinder to be shifted backwardly and forwardly on the frame to adapt the machine to flues of different lengths. Said push-off cylinder is supported across the channel walls of the chamber 14 through the medium of the bracket 142', the flanges 152 of which rest on the flanged plate 13 that bound said chamber and is secured in different longitudinal positions of adjustment by the cam-lock 153, best shown in Figures 1, 2, 16 and 17. The valve 24 which is connected to the push on cylinder 142 through the pipe 39, hose 150 and inlet connection, is operated by a snap action of its square-toed lever, it being understood that said valve does not require to be held open any longer than is necessary to push the tube on to its driving chuck 77. Therefore the spring 145 pushes the piston 143 rearwardly and resets this mechanism for another operation.
- Means are located at the front end of the 85 machine for cutting off a portion of the reduced end f of the tube F. Said cutting mechanism is best shown in Figures 1 and 5, and is made as follows:
- 160 designates a cylindric bar which has reciprocating and rocking mounting in a cylinder 161, constituting a fixed or unitary part of the front of the machine frame. Said bar 160 is formed at its front end to constitute a piston 162 which has sliding 90 movement in the cylinder 161. Said bar is made of slightly less diameter than the internal diameter of the cylinder, but engages with a guiding fit an annular rim 163 at the rear end of said cylinder 161. 165 designates 100 a hardened cutter disk which has a beveled cutting edge. It is fastened off center to the rear end of the bar 160, as by means of a screw 166, so that rotation of said bar 160 will move the edge of the cutter towards and from the reduced end of the flue when connected to said chuck.
- 167 designates a hand lever that is fixed to the rear end of said bar 160. With this construction it will be noted that when the reduced end of the flue is fixed on said driving chuck and the hand lever is swung to one side of the center of its axis, it will cause the hardened cutting edge of the disk to move eccentrically towards the wall of the 110 reduced part of the tube to cut it away. The disk is held on said tube while still rotating with the chuck (and at this time the cleaner rolls 60 can be moved by its operating mechanism out of contact with the rotating flue). 115 Contact of the cutter with the flue will sever the same, and thereafter air through valve 24 and port 168 is admitted to the cylinder in front of the piston 162 so as to force the cutter and flue rearwardly while still in contact with the flue. This is done after the flue driving chuck is disengaged from the flue. The cut off portion of the flue is then replaced by a safe end and the parts are in 120 position to weld said safe end on the flue. It 125 130

- is a distinct advantage to construct the machine so that the cutting and welding may be made with a minimum manual handling of the flue.
6. In addition to the means for severing or cutting the tube at its reduced end, I have provided means for cutting the flue in its larger diameter, and near its rear end in generally the same way as described. The 10 latter cutter means are generally similar to the front cutting means, with the exception that it is hand operated, and is designed to remove and substitute the rear end of the flue while the flue is still in the machine.
15. Said latter cutter mechanism embraces a bar 175 that is mounted to be rocked on its axis in a tube or cylinder 176, which is supported centrally of the machine by a suitable bracket 177 and locked in said bracket 20 by a locking device 178. The cylinder mounting or bracket is locked on the frame by the eccentric locks 179 similar to that described in connection with the mounting for the push on cylinder. Eccentrically and 25 rotatively mounted on the front end of the cutter bar 175 is a bevel cutter disk 180, as by a screw 181. The said rocking cutter bar 175 is rocked on its axis by a hand lever 182 to bring the cutter into cutting engagement 30 with the tube while the tube is rotated by its driving connection to the chuck 77. After the flue has been severed, the rear length thereof is removed, and if it be desired to braze or weld another length to the flue, the 35 proper length tube may be lowered on to the cradle rolls 75, and forced with its end against the cut end of the flue by the thrust plate 140, hereinbefore described, whereupon the tubes can be joined by a proper welding 40 operation while in the machine and during rotation of the flue, if desired.
- It sometimes occurs that it is desirable to 45 electrically weld flue ends to a flue after it has been cleaned in this machine, and the machine is so constructed and arranged that the flue parts or the joint to be electrically welded can be treated, to make it in readiness for the welding machine.
- 185 (Figures 11, 12 and 13) designates a 50 bracket frame that is held against the inner plain side of one of the channel side members. As shown, the bracket frame is provided at its upper end with a hook 186 that lies over the upper flange of the side frame member 13 and embraces the upper flange of said member, and can be locked to the frame by means of a bolt 187. The bolt 187 may extend through a slot 188 of the frame flange so as to adjust this accessory longitudinally 55 of the machine frame.
- Said mechanism embraces as a part thereof a steel scraper and end squaring tool 190 that is formed with an end scraper fin 191 and a cylindric facing edge 192. It is fixed 60 to a sliding tool head 191' which is mounted to slide in and out in a suitable guideway formed by an instanding guide 192'. The tool is attached to the inner end of said sliding tool head by a screw 193 and is braced by a backing bead or squared shoulder. The sliding tool head is adapted to be forced inwardly towards the tube by a vertically swinging operating lever 195 that is pivoted between its ends at 196 to the front stud bracket 197, fixed to the frame 185 in any suitable manner. The lower end of said operating lever extends into and through a notch 198 of the sliding tool head to bear against a shoulder 199 to move the tool head inwardly when the lever 195 is swung in the proper direction; and a pull back pin 200 extends across said notch 198 to be engaged by the lower end of the operating lever to withdraw said sliding tool head and the tool carried thereby.
- The said operating lever 195 is formed at its upper end with a slot 201 through which extends a shaft 202 that is pivoted at 203 to the upper end of the bracket member 185. Said shaft is threaded at its outer end to receive a threaded feed wheel 204, the hub of which wheel has bearing against the inner face of said operating lever. Surrounding said shaft and interposed between said operating lever and a fixed part of the frame is a spiral compression spring 205 which normally acts on the operating lever 195 to withdraw the sliding tool head from the flue position.
- The scrapings from the flue fall into the 100 said hopper 15 that is supported beneath the chamber 14. The main portion of the bottom of the hopper is inclined towards one side of the machine and said bottom includes the drop door 16 before described.
- From an inspection of Figure 5, it will be noted that the cylinder 161 is provided with an exhaust vent 161' to permit release of air in rear of piston 162 when the flue is being forced backwardly after a cutting-off operation, and thus prevent the said piston from violently striking the cylinder end 163.
- It will also be observed that the clutch pins 131 are normally held inwardly by an open spring 131' which surrounds the clutch and engages grooves in the roughened heads 132 of said clutch pins or studs.
- I claim:
1. In a flue cleaning machine, flue supporting elements and rotary driving means, the latter engageable with an end of a flue, a series of lengthwise spaced cleaner elements adapted by gravity for movement from the tube cleaning position, and means to resiliently press the series of cleaner elements against the exterior of the flue.
  2. In a flue cleaning machine, flue supporting elements and rotary driving means, the latter engageable with an end of a flue, a series of lengthwise spaced cleaner ele-

ments adapted by gravity for movement from the tube cleaning position, and means to resiliently press the series of cleaner elements against the exterior of the flue, each 5 series of cleaner elements comprising a plurality of endwise disposed exteriorly toothed rotative rolls independently rotative on their axes.

3. In a flue cleaning machine, flue supporting elements and rotary driving means, the latter engageable with an end of a flue, a series of lengthwise spaced cleaner elements 10 adapted by gravity for movement from the tube cleaning position, and means to resiliently press the series of cleaner elements 15 against the exterior of the flue, each series of cleaner elements comprising a plurality of endwise disposed exteriorly toothed rotative rolls independently rotative on 20 their axes, the cleaner elements of each series being independently rotative on a common axis and exteriorly circumferentially toothed and each element being longitudinally recessed to intersect the teeth of the 25 cleaner elements.

4. In a flue cleaning machine, flue supporting elements and rotary driving means, the latter engageable with an end of a flue, a series of rotative toothed cleaner rolls 30 spaced along said support, each comprising a pendant frame to support the axles of the shafts of the rolls and adapted by gravity to swing from the tube cleaning position, and means to resiliently press the series of 35 cleaning rolls against the sides of a flue.

5. A flue cleaning machine comprising an elongated chamber, flue cleaning devices at the sides of the chamber adapted for relative 40 rolling contact with a flue therein, thrust bars at the sides of the chamber having cam surfaces, cam pins engaging said surfaces and acting to force said cleaners toward each other and the flue cleaning position, and means for giving endwise movement to said 45 thrust bars to act through said pins on said cleaners.

6. A flue cleaning machine comprising an elongated chamber, flue cleaning devices at the sides of the chamber adapted for relative 50 rolling contact with a flue therein, thrust bars at the sides of the chamber having cam surfaces, cam pins engaging said surfaces and acting to force said cleaners toward each other and the flue cleaning position, means for giving endwise movement to said thrust bars to act through said pins on said cleaners, and means to vary the throw of the 55 thrust bars.

7. A flue cleaning machine comprising an elongated series of flue cleaner elements at the sides of the cleaning position of a flue, thrust bars at the sides of the flue cleaning 60 position and having cam surfaces, cam pins engaging said surfaces and acting to force said cleaner elements toward the flue clean-

ing position, and means for giving endwise movement to the cams of the thrust bars.

8. A flue cleaning machine comprising an elongated series of flue cleaner elements at the sides of the cleaning position of a flue, 70 supports at the sides of the flue cleaning position and having cams, cam pins engaging said cams and acting to force said cleaner elements toward the flue cleaning position, means for giving endwise movement to the said cams, and means to vary the throw of the said cams.

9. A flue cleaning machine comprising an elongated series of flue cleaner elements at the sides of the cleaning position of a flue, 80 thrust bars at the sides of the flue cleaning position to control the movements of the flue cleaner elements, and operating means for the thrust bars embracing a double acting cylinder provided at each end with a controllable air inlet, and a piston in said cylinder 85 connected to said thrust bars.

10. A flue cleaning machine comprising an elongated series of flue cleaner elements at the sides of the cleaning position of a flue, thrust bars at the sides of the flue cleaning 90 position to control the movements of the flue cleaner elements, operating means for the thrust bars embracing a double acting cylinder provided at each end with a controllable 95 air inlet, a piston in said cylinder having a rod connected to said thrust bars, and means associated with an extension of the piston rod to vary the throw of the piston and the consequent movement of the cleaner elements 100 toward the flue cleaning position.

11. A flue cleaning machine comprising a series of cleaner rolls mounted on frames to be movable towards and from a flue in cleaning position, with means to give relative 105 rotation to the flue and rolls, means for moving the rolls toward and from the flue cleaning position, embracing thrust bars at the sides of the rolls and a double acting cylinder 110 having a piston therein connected to and operating said thrust bars.

12. A flue cleaning machine comprising a series of cleaner rolls mounted on frames to be movable towards and from a flue in cleaning position, with means to give relative rotation to the flue and rolls, means for moving the rolls toward and from the flue cleaning position, embracing thrust bars at the sides of the rolls, and a double acting cylinder 115 having a piston therein connected to and operating said thrust bars through a resilient connection between said thrust bars and said cleaner elements.

13. A flue cleaning machine comprising a series of cleaner rolls mounted on frames to be movable towards and from a flue in cleaning position, with means to give relative rotation to the flue and rolls, and means for moving the rolls towards and from the flue 120 cleaning position, embracing cammed end- 130

wise movable thrust bars at the sides of the rolls, means for giving endwise movement to said thrust bars, thrust pins engaging the cams of the thrust bars and yieldingly and resiliently connected to said roll frames, and means to give endwise movement to the thrust bars.

14. A flue cleaning machine comprising a series of cleaner rolls mounted on frames to be movable towards and from a flue in cleaning position, with means to give relative rotation to the flue and rolls, and means for moving the rolls towards and from the flue cleaning position, embracing cammed endwise movable thrust bars at the sides of the rolls, means for giving endwise movement to said thrust bars, thrust pins engaging the cams of the thrust bars, and elliptical springs connected to said roll frames through which thrust pressure of the said pins is applied to said frames.

15. A flue cleaner comprising an elongated series of pneumatically flue controlled cleaner elements, a pneumatically controlled clutch to engage one end of the flue to rotate it, a pneumatically controlled push on mechanism to endwise engage the flue with said clutch, a source of air supply, pipe connections between said source and the said operating mechanisms, and a series of valves to control said pipe connections located as a bank at one end of the machine, and provided with manually operable handles, whereby the functions of said operating mechanisms can be controlled from a single position of an operator.

16. A flue cleaner comprising an elongated series of pneumatically flue controlled cleaner elements, a pneumatically controlled clutch to engage one end of the flue to rotate it, a pneumatically controlled push on mechanism to endwise engage the flue with said clutch, a source of air supply, pipe connections between said source and the said operating mechanisms, and a series of valves to control said pipe connections located as a bank at one end of the machine, and provided with manually operable handles, whereby the functions of said operating mechanisms can be controlled from a single position of an operator, all of said valves being spring operated to close them, and certain of the handles being equipped with cams to lock open the valves thereby controlled, the other levers opening with a snap action when manual pressure is removed therefrom.

17. In a flue cleaning machine, the combination with a series of cleaners arranged in an endwise series at the side of a flue cleaning position, driving means engaging an end of the flue to rotate it while in contact with the cleaners, means for severing the flue end at the rotating means while engaged in driving relation therewith, and a throwoff means engaging the flue to discon-

nect it from said driving means and to permit the removal of the cut-off piece and the substitution of a safe end, whereby said safe end may be welded to the flue while in the machine.

18. In a flue cleaning machine, the combination with a series of cleaners arranged in an endwise series at the side of a flue cleaning position, means engaging an end of the flue to rotate it while in contact with the cleaners, a rock shaft parallel to the flue position while being cut, an eccentric beveled blade carried by and adapted through rocking of said shaft to be brought into cutting relation to the flue end, and means for giving endwise movement to the said rock shaft to separate the flue from the cut-off portion thereof.

19. In a flue cleaning machine, the combination with a series of cleaners, arranged in an endwise series at the sides of a flue cleaning position, means engaging the end of the flue to rotate it while in contact with the cleaners, a rock shaft parallel to the flue position, an eccentric beveled blade on, and adapted through rocking of, said shaft to be brought into cutting relation with the flue, a cylinder to contain said rock shaft, said rock shaft having a piston which operates in said cylinder, and a valved air connection to the cylinder to give endwise movement to said piston and to said rock shaft.

20. In a flue cleaning machine, the combination with a series of cleaners, arranged in an endwise series at the sides of a flue cleaning position, means engaging the end of the flue to rotate it while in contact with the cleaners, a rock shaft parallel to the flue position, an eccentric beveled blade on, and adapted through rocking of, said shaft to be brought into cutting relation with the flue, a cylinder to contain said rock shaft, said rock shaft having a piston which operates in said cylinder, and a valved air connection to the cylinder to give endwise movement to said piston and to said rock shaft, said cylinder being provided near its front end with an exhaust port to avoid clashing of the said piston with the cylinder end.

21. A flue cleaning machine comprising a chamber, a series of flue cleaners endwise disposed along the chamber at one side of a cleaning position of the flue in said chamber, a clutch to engage one end of the flue to rotate it, and a push on device to engage the other end of the flue to push the flue onto said clutch.

22. A flue cleaning machine comprising a chamber, a series of flue cleaners endwise disposed along the chamber at one side of the cleaning position of the flue in said chamber, a clutch to engage one end of the flue to rotate it, and a push on device to engage the other end of the flue to push the flue onto said clutch, said push on device

embracing a cylinder at the rear end of the machine, a piston therein having a rod extending through one wall of the cylinder, a push on disc fixed to said rod, and means to supply air under pressure to said cylinder.

23. A flue cleaning machine comprising a chamber, a series of flue cleaners endwise disposed along the chamber at one side of the cleaning position of the flue in said chamber, 10 a clutch to engage one end of the flue to rotate it, and a push on device to engage the other end of the flue to push the flue onto said clutch, said push on device embracing a cylinder at the rear end of the machine, a 15 piston therein having a rod extending through one wall of the cylinder, a push on disc fixed to said rod, means to supply air under pressure to said cylinder, and a buffer spring adapted to be compressed between 20 said piston and the end of the cylinder having the function of yieldingly forcing the other end of the flue on the clutch and of retracting the piston.

24. A flue cleaning machine comprising a chamber, an endwise series of flue cleaner 25 elements therein at the side of the flue cleaning position in said chamber, means to bring the cleaners and flue in operative relation, and means to insert and remove a flue from

the chamber comprising a pair of pneumatically controlled saddles having an air connection to raise them to receive a flue, and upon opening of the air connection to permit the saddles to drop with a flue to carry the latter into the flue cleaning position.

25. In a flue cleaner, a series of endwise disposed cleaning rolls arranged end to end, and a support therefor embracing a shaft about which the rolls turn, the rolls of each group being independently rotatable on the 40 shaft, and said rolls being exteriorly threaded to form cutting surfaces, said threads being interrupted to produce angularly spaced cutting edges.

26. In a flue cleaner, a series of endwise 45 disposed cleaning rolls arranged end to end, and a support therefor embracing a shaft about which the rolls turn, the rolls of each group being independently rotatable on the shaft, and said rolls being exteriorly threaded to form cutting surfaces, and each roll being provided with a plurality of angularly 50 spaced recesses intersecting said threads.

In witness whereof I claim the foregoing as my invention, I hereunto append my signature this 6 day of August, 1924.

JOHN T. McGRATH.
